UNITED STATES PATENT OFFICE

2,491,900

COIN CONTROLLED MECHANISM

Emery Mihalek, Chicago, Ill., assignor to O. D. Jennings & Company, Chicago, Ill., a corporation of Illinois

Application June 17, 1944, Serial No. 540,778

4 Claims. (Cl. 194—10)

1

This invention relates to coin controlled mechanisms and more particularly to mechanisms which may be operated by two or more coins of different values.

One of the objects of the invention is to provide a coin controlled mechanism which is operated thru a single cycle by coins of different values and which will return change when a coin of a higher value is employed.

Another object of the invention is to provide a coin controlled mechanism in which coins of the lower value are dispensed from a receptacle which receives such coins inserted in the mechanism when a coin of higher value is inserted in the mechanism to make change.

Still another object of the invention is to provide coin controlled mechanism in which an insertion of a coin of higher value is prevented when no coins of lower value are available to make change.

A still further object of the invention is to provide a coin controlled mechanism in which insertion of a coin of the lower value resets the mechanism so that a coin of higher value can thereafter be inserted.

The above and other objects and advantages of the invention will be more readily apparent from the following description when read in connection with the accompanying drawing, in which:

Figure 1 is a perspective view of a machine embodying the invention; and

Figure 2 is a diagrammatic view of the operating mechanism of the machine.

As illustrated in Figure 1, the invention is embodied in a dispensing machine including a cabinet 10 containing dispensing mechanism of any desired type for dispensing either of a plurality of different types of articles. The type of article to be dispensed may be selected by a selector switch 11 which selects one or the other of the dispensing mechanisms so that the selected article will be dispensed.

According to the present invention the machine may be operated by coins of different values as for example, by either a 5-cent piece or a 10-cent piece. For this purpose, two coin slots 12 and 13 are provided, the slot 12 being adapted to receive nickels and the slot 13 being adapted to receive dimes. When a nickel is inserted in the slot 12 the machine will be operated to dispense one article and when a dime is inserted the machine will be operated to dispense one article and to return a nickel thru the coin return opening indicated at 14.

2

As shown in Figure 2, nickels inserted in the slot 12 pass thru a chute 15 into a spurious coin detector 16. Any spurious coins inserted in the slot will be returned thru the coin return opening 14 by a coin return duct 17 while good coins inserted in the chute 15 will pass thru a chute 18. Dimes inserted in the slot 13 will similarly pass thru a chute 19 into a spurious coin detector 21. Any spurious coins inserted in the slot 13 will be returned thru the duct 17 while good coins will pass thru the chute 22.

Nickels passing thru chute 18 are received in a spoked wheel 23 by which they are held in a position visible from the exterior of the machine 15 during several cycles of operation. Dimes passing thru the chute 22 are received by a similar spoked wheel 24 connected to the wheel 23 thru gears 25 on the wheels, both of which mesh with an idler gear 26.

20 The gears 25 and the dispensing mechanism (not shown) are driven by an operating motor 27 which drives the dispensing mechanism and which is provided with an extended shaft indicated at 28. The shaft 28 carries a pair of cams 29 and 31 as well as an intermittent driving member 32. The driving member as shown, comprises a rear disc 33 carrying a pair of diametrically spaced pins 34. A segmental disc 35 overlies the disc 33 and is formed with a portion of its circumference circular with diametrically opposite depressions 36 registering with the pins 34.

35 The intermittent drive mechanism is completed by a disc 37 formed with a series of arcuate portions, shown as five in number, to interfit with the arcuate portions of the disc segment 35 and having a series of radial slots 38 between the adjacent arcuate portions. The disc 37 is connected to one of the gears 25 so that when it is operated 40 both of the spoked wheels 23 and 24 will be turned to equal extent in the same direction.

45 The motor is adapted to be operated thru one-half revolution per cycle as will be explained later. When the motor operates one or the other of the pins 34 enters one of the slots 38 to turn the disc 37 thru one-fifth revolution of the driving member 32. Upon completion of an operation the disc 37 will be held against further rotation by engagement of one of the arcuate portions of this disc with one of the arcuate ends 50 of the disc member 35.

55 The motor is adapted to be supplied with operating current from supply lines 39 and 41 which may be the usual household electric current supply circuit. One side of the motor is con-

nected directly to the line 39 thru a wire 42 and the opposite side is connected to a wire 43. The wire 43 is connected to one side of each of a pair of contacts 44 and 45, the other side of which is connected thru a wire 46 to the supply line 41. The contacts 44 and 45 are normally opened and are adapted to be closed by relays 47 and 48 operating armatures 49 and 51 respectively when the coils 47 and 48 are energized.

The coil 47 is connected thru a wire 52 to one side of a pair of switch contacts 53 which are operated by a lever 54 projecting into the nickel coin chute 18 to be closed each time a nickel passes thru the coin chute. The other side of the pair of contacts 53 is connected thru a wire 55 to a contact 56 adapted to engage a contact 57 under the control of the cam 29. The contact 57 is connected as shown directly to the wire 46 which leads to the supply line 41.

The armature 49 operated by the coil 47 also controls a pair of switch contacts 58 connected at one side to the wire 52 and at the other side to the contact 56 thru a wire 59. The side of the coil 47 opposite the wire 52 is connected directly to the supply line 39 thru a wire 61.

When a nickel is inserted in a machine and passes thru coin chute 18 it temporarily closes the contacts 53. This initially establishes a circuit thru the coil 47 from the line 39 thru line 61, coil 47, line 52, contacts 53, wire 55, contacts 56 and 57, and wire 46 to the supply line 41. This energizes the coil 47 causing it to attract the armature 49 and closing the switches 44 and 58. The contacts 58 form a holding circuit from supply line 39 thru the wire 61, coil 47, contacts 58, wire 59, switch blades 56 and 57 and wire 46 to supply line 41. The coil 47 is therefore held energized as long as switch contacts 56 and 57 are in engagement.

As soon as the contacts 44 close the motor 21 is energized from supply line 39 thru wire 42, motor 21, wire 43, switch 44 and wire 46 to supply line 41. The motor, therefore, begins to operate to drive the dispensing mechanism and to drive the shaft 28.

The cam 29 mounted on shaft 28 is formed with two raised lobes separated by two opposite depressed portions and the switch blade 57 is formed with an extension having a projection 62 thereon engageable with the raised lobes of the cam. The cam normally occupies the position shown in which the projection 62 is opposite a depressed portion of the cam so that the switch blade 57 can spring downwardly into engagement with the contact 56. After the motor has turned the shaft 28 thru a relatively small angle, one of the raised lobes of the cam 29 will engage the projection 62 to move the switch blade 57 out of engagement with the blade 56 and into engagement with a contact 63 connected to the wire 43. When this occurs the motor will be connected across the supply line thru wires 42, switch blades 63 and 57 and wires 43 and 46. However, since the circuit between contacts 56 and 57 is interrupted, the coil 47 will be de-energized and the armature 49 will drop to the position shown allowing the switches 44 and 58 to open. The motor will continue to operate until the projection 62 moves off of the raised lobe of cam 29 at which time the blade 57 will drop to the position shown opening the motor circuit between the contacts 57 and 63. The position at which this occurs will always be the same so that the motor will always stop with the cams and the spoked wheels 23 and 24 in the same positions. With a two-lobed

cam as shown, it will be seen that each operating cycle of the mechanism requires half of a revolution of the shaft 28.

During rotation of the shaft 28 as above described, the intermittent drive member 32 will drive the spoke wheels 23 and 24 thru one-fifth of a revolution. The coin passing thru the chute 18 will be received in the space between the uppermost spokes of the wheel 23 and a coin previously received in the wheel will be discharged in the lower part thereof. A coin receptacle 64 is provided to receive coins from the wheel 23 and to hold them in a vertical stack as shown at 65. After the receptacle 64 is filled any additional coins will be carried by the chute 66 to a container provided therefor.

Passage of a dime thru chute 22 operates a pair of switch blades 67 thru an operating lever 68 projecting into the chute temporarily to close the blades 67. One of the blades 67 is connected to the wire 55 and the other is connected thru a wire 69 to a switch contact 71. The blade 71 is engageable with a switch blade 72 which is connected thru a wire 73 to the lower end of the coil 48. The upper end of coil 48 is connected thru a wire 74 to the supply line 39. The switch blade 71 is movable with a blade 75 which is connected to the wire 82. The blade 75 is adapted to engage a blade 77 connected thru a wire 78 to one side of a solenoid 79 the other side of which is connected directly thru a wire 81 to the supply line 39. The wire 69 is also connected thru a wire 82 to one side of a holding circuit switch 83 operated by the armature 51 the other side 35 of which is connected to the wire 59.

When a dime is inserted in the machine, it temporarily closes the switch 67 establishing a circuit thru the coil 48, from the line 39, thru the wire 74, coil 48, line 73, wire 69, switch 67, wire 55, switch blades 56 and 57 and wire 46 to the supply line 41. This energizes the coil 48 raising the armature 51 and closing the switches 45 and 83. The switch 83 establishes a holding circuit thru the coil 48 in parallel with the switch 67 from line 69 thru the wire 82, switch 83, to line 59 thru switch contacts 56 and 57 and wire 46 to the supply line 41. Thus the coil 48 will remain energized as long as the contacts 83 are closed.

50 The motor 21 is energized by closing of the switch 45 from line 39 to wire 42, the motor, wire 43, switch 45, and wire 46 to supply line 41. Operation of the motor is thus initiated to drive the dispensing mechanism and to turn the shaft 55 28 and the cams 29 and 31. According to one feature of the invention, insertion of a dime operates the dispensing mechanism thru one cycle and returns a nickel in change. For this purpose, a slider 84 is provided formed with an opening to receive a nickel from the receptacle 64. The slider is connected to a core moved by the solenoid 79 so that the opening therein will be moved into register with the change chute 85 when the solenoid is energized. Thus each time the solenoid 65 79 is energized the slider 84 will remove a nickel from the bottom of the stack in the receptacle 64 and dispense it thru the change chute 85.

The solenoid 79 is connected to the line 39 thru the wire 81 and thru the wire 78 to the switch 70 blade 71. The cam 31 is a double lobed cam similar to the cam 29 and is formed in its raised lobe portions with further raised projections 86. As this cam is rotated one of the projections 86 will raise the switch blades 72 moving both blades 71 and 72 in a clockwise direction. The blade 71

moves blade 75 into contact with blade 77 when the projection 86 moves the blade 72. When this contact occurs a circuit will be completed thru the solenoid 79 from line 81 thru the solenoid, wire 78, contacts 75 and 77, wire 82, contacts 83, contacts 56, 57 and wire 46 to the supply line 41. Since the contacts 83 are closed only when a dime has been inserted in the machine, the solenoid 79 cannot be energized upon closing of contacts 75 and 77 when the motor is operated by insertion of a nickel.

As the shaft 28 continues to turn the switch blade 72 will drop off of a lobe of the cam 31 to open the circuit between blades 71 and 72. This will break the holding circuit for the coil 48, de-energizing the coil and allowing the armature 51 to drop to the position shown in which contacts 45 and 83 are open. However, before this occurs the cam 29 will have raised the blade 57 engaging it with the blade 63 and completing a circuit thru the motor as described above in connection with nickel operation. Thus, the motor will continue to run until the upper projection 62 drops off a lobe of the cam 29 at which time the parts will be in the position shown with the blade 72 elevated by the cam 31 into engagement with the blade 71.

In order to prevent insertion of a dime into the machine when no change is available in the receptacle 64, a feeler 87 is provided movable thru an opening in the side of the receptacle 64 to engage coins therein. The feeler is urged inwardly toward the receptacle by a spring 88 and is formed on its lower surface with a projection 89 controlling a switch 91. When the feeler moves into the receptacle in the absence of coins therein to the position shown in Figure 2, the switch 91 will be opened. One side of the switch 91 is connected thru the wire 81 to the supply line 39 and the other side is directly connected thru a wire 92 to a coil 93. The coil is connected thru a wire 94 to the supply line 41 so that it is energized whenever the switch 91 is closed.

The coil 93 controls a blocking finger 95 which projects into the coin detector box 21. The coil 93 is energized, holds the finger 95 out of the box 21 and when it is de-energized it allows the finger 95 to move into the box 21. The finger 95 operates to divert any dimes inserted thru the chute 19 directly into the coin return chute 17. Thus when there is no change in the receptacle 64 any dimes inserted in the machine will be returned without passing thru the operating chute 22.

Each time a nickel is inserted in the machine the feeler 87 is retracted so that it will again engage coins in the receptacle 64 and permit insertion of dimes. For this purpose a solenoid 96 is provided having its movable core 97 connected to a lever 98 which is connected at one end to the finger 87. When the solenoid 96 is energized the finger 87 will be moved to the right so that it can engage a nickel in the receptacle 64.

One side of the solenoid 96 is connected to the wire 81 and the other side is connected thru a wire 97 to the wire 52. When the switch 53 is closed by insertion of a nickel the solenoid 96 will be energized from wire 97, thru the switch 53, wire 55, contacts 56 and 57 and wire 46 to the supply line 41. Engagement of the finger 87 with a coin in the receptacle 64 will permit the switch 91 to close to energize the coil 93 and move the blocking finger 95 out of the coin box 21. With the parts in this position dimes can be inserted

and can pass thru the coin chute 22 to operate the mechanism as described above.

While one embodiment of the invention is shown and described in detail herein it is to be understood that this is illustrative only and is not intended as a definition of the scope of the invention, reference being had for this purpose to the appended claims.

What is claimed is:

1. A coin controlled mechanism comprising a pair of coin chutes to receive coins of different values, means operated by a coin passing thru the chute for the coin of lower value to operate the mechanism thru one operating cycle, a receptacle to receive coins of the lower value from the chute therefor, means operated by a coin passing thru the chute for the coin of higher value to operate the mechanism thru one operating cycle and simultaneously to dispense a coin of lower value from the receptacle, a feeler engageable with coins in the receptacle, resilient means urging the feeler toward the receptacle, means operated by movement of the feeler into the receptacle beyond its normal coin engaging position to prevent passage of a coin thru the chute for coins of the higher value when the receptacle is empty and means operated by a coin passing through the chute for the coin of lower value to retract the feeler from the receptacle.

2. A coin controlled mechanism comprising a pair of coin chutes to receive coins of different values, an operating motor, switch means operated by passage of a coin thru the chute for coins of lower value to energize the motor for operation thru one cycle of the mechanism, switch means controlled by passage of a coin thru the chute for coins of higher value to energize the motor for operation thru one cycle of the mechanism, a receptacle to receive coins of the lower value from the chute therefor, means controlled by the last named switch means upon each closure thereof to dispense a coin from the receptacle, a feeler movable toward and away from the receptacle to engage coins in the receptacle, means normally urging the feeler toward the receptacle, a switch operated by the feeler upon movement thereof toward the receptacle beyond its normal coin engaging position when the receptacle is empty, means controlled by the last named switch to prevent passage of a coin thru the chute for coins of higher value when the receptacle is empty, and means operated by passage of a coin thru the chute for coins of lower value to move the feeler away from the receptacle.

3. A coin controlled mechanism comprising a pair of coin chutes to receive coins of different values, an operating motor, cam controlled switches operated by the motor, circuits for the motor controlled by the switches to energize the motor during one cycle of operation of the mechanism, coin controlled switches operated by passage of a coin thru either of the chutes to initiate operation of the motor, a receptacle to receive coins from the chute for coins of lower value, a feeler engageable with coins in the receptacle, resilient means urging the feeler toward the receptacle to engage coins therein, means operated by passage of a coin thru the chute for coins of the higher value to dispense a coin from the receptacle, means operated by the feeler to prevent passage of a coin thru the chute for coins of higher value when the feeler fails to engage a coin in the receptacle and

means operated by a coin passing through the chute for the coin of lower value to move the feeler away from the receptacle against the resilient means.

4. A coin controlled mechanism comprising a pair of coin chutes to receive coins of different values, an operating motor, cam controlled switches operated by the motor, circuits for the motor controlled by the switches to energize the motor during one cycle of operation of the mechanism, coin controlled switches operated by passage of a coin thru either of the chutes to initiate operation of the motor, a receptacle to receive coins from the chute for coins of lower value, a feeler movable toward and away from the receptacle to engage coins in the receptacle, means normally urging the feeler toward the receptacle, means operated by passage of a coin thru the chute for coins of the higher value to dispense a coin from the receptacle, means operated by movement of the feeler toward the re-

ceptacle beyond its normal coin engaging position, to prevent passage of a coin thru the chute for coins of higher value when the feeler fails to engage a coin in the receptacle, and means operated by passage of a coin thru the chute for coins of the lower value to move the feeler away from the receptacle.
